UNITED STATES PATENT OFFICE.

NORMAN D. STURGES, OF BROOKLYN, NEW YORK, ASSIGNOR TO MULTIPLE STORAGE BATTERY CO., A CORPORATION OF NEW YORK.

MOLD FOR CASTING BATTERY-GRIDS.

1,317,333.

Specification of Letters Patent. Patented Sept. 30, 1919.

Application filed April 24, 1918. Serial No. 230,433.

To all whom it may concern:

Be it known that I, NORMAN D. STURGES, a citizen of the United States, residing in Brooklyn, in the county of Kings and State 5 of New York, have invented certain new and useful Improvements in Molds for Casting Battery-Grids, of which the following is a full, clear, and exact description.

My invention relates to the casting of lead 10 grids of a kind suitable for storage batteries, my purpose being to facilitate the casting of a comparatively thin and light grid, free from blow holes, bubble pockets and similar defects due to practical difficulties arising 15 from the presence of air in the casting dies.

My invention is of special utility in the matter of casting comparatively thin and frail grids, to be used in making thin and light battery plates.

20 In casting such grids, and especially in instances in which the object is to produce exceedingly thin battery plates—say one thirty-second to one-sixteenth of an inch in thickness—it is a very difficult matter to 25 cause the molten lead to flow properly into the various casting grooves intended for it, owing to the fact that these grooves are quite small and contain air, and that various bodies of this air are liable to become pock- 30 eted in and held by the molten metal. If, now, ordinary air vents be provided to facilitate the escape of the trapped air, the molten metal tends to follow the air into 35 the air vents, and thus give rise to other difficulties.

What I seek to do, therefore, is to provide casting grooves for receiving and retaining the molten metal, and also a number of air 40 passages for receiving air from the grooves and for discharging the air thus received. In doing this I give such form to the parts that while the air can find its way from the network of grooves to the various air ducts, the molten metal is unable to follow the air 45 and thus is unable to clog the air passages.

Reference is made to the accompanying drawing forming a part of this specification, and in which like reference numerals indicate like parts throughout the several figures.

Figure 1 is a fragmentary front elevation of one of my improved die plates used in casting.

Fig. 2 is a view, partly in elevation and 55 partly in end section, of the mold complete.

Fig. 3 is an enlarged section, on the line 3—3 of Fig. 1, looking in the direction indicated by the arrows.

The two jaws of a mold are shown at 3, 4, and are connected together by a hinge 5 60 in the usual or any desired manner. Two die plates are shown at 6, 7, and are removable independently of each other. These plates are preferably made of refractory metal, such as steel, but may be made of 65 any other material commonly used in this art for analogous purposes.

Each die plate 6, 7, is provided with casting grooves 8, 9, 9^a, merging into each other and thus connected together after the manner of a labyrinth. Each die plate is further provided with air passages 10, disposed parallel to each other and terminating in the open air. Each air passage 10 extends nearly the width of the die plate, and is 70 spaced from the nearest adjacent casting groove 8, 9, 9^a of the same die plate by a distance at least equal to the proximate thickness of the plate.

Each die plate is by virtue of the casting 80 grooves 8, 9, 9^a scored off into facets 12, and located in the center of each facet is an air hole 13, merging into and virtually forming an extension of the adjacent air passage 10.

Each facet 12 is further provided with a set of air ducts 14, each of the form indicated in Fig. 3 and merging into the air hole 13 of the same facet. That is to say, each duct 14 has the proximate form of a 90 wedge, its deepest portion being where it merges into the hole 13, the duct becoming shallower as it leads away from this hole, the outer end of the duct terminating short of the adjacent corner of the facet. There 95 is thus left, in the corner of each facet, a distinct wall 15 of the die plate. This wall is for the purpose of preventing the travel of molten lead into the ducts 14 and the air hole 13, while allowing the air to make its 100 escape, as hereinafter more completely described.

Each die plate is further provided with an air vent 16, preferably branching in form, as shown at the left of Fig. 1. 105 This air vent is merely to allow the free escape of air from the mold, and particularly from the outer portions thereof, in the usual or any desired manner.

The die plates 6, 7 are mates; that is, the 110

face of each die plate matches the face of the other, so that when the two die plates are brought together, as in Fig. 2, each facet is in juxtaposition with some other facet, and the various grooves of one plate are caused to merge into corresponding grooves of the other plate. Hence each air hole 13 in one plate is in alinement with a similar air hole in the opposite plate, as indicated in Fig. 2. The two die plates are in so-called actual face contact each with the other. Practically speaking, they are jammed together, face to face.

The mold is provided with an inlet opening 17 and with gate holes 18, to facilitate the introduction of the molten metal.

The operation of my device is as follows:

The parts being assembled and arranged as above described, molten lead is poured into the mold and finds its way into the casting grooves 8, 9 and 9^a and in so doing tends to displace the contained air therefrom.

A portion of this air, located comparatively near the outside of the mold and easily expelled, is readily forced out through the air vent 16.

Most of the trapped air, however, works its way out by creeping between the juxtaposed facets 12 of the two die plates, and entering the air ducts 14 and thence passing through the ducts 14 and into the air passages 10.

This part of the action, however, should not be misunderstood. The air does not rush freely from the molding grooves through the ducts 14, and into the air holes 13. What the air does in this connection is to spread out into the form of capillary films, each of the proximate size of a facet 12, and having done that it gradually gathers into the ducts 14, and thence flows into the holes 13; this action being facil-

tated by the increasing depth of the ducts 14, reckoning from the outer ends thereof 45 and toward the holes 13. The molten metal, however, is unable to pass the juxtaposed walls 15, and thus can not pass into the ducts 14. The point is that the air, by virtue of its mobility, can spread out into 50 a film and thence can gather itself together and enter the air holes 13, but that owing to the closeness of the fit of the juxtaposed facets 12 the molten lead, having less mobility and poorer capillarity than air, is 55 confined within the casting grooves. Each wall 15 acts selectively as between the air and the lead.

I do not limit myself to the precise arrangement shown, as variations may be 60 made therein without departing from the spirit of my invention, the scope of which is determined by my claims.

I claim:

1. In a device of the character described, 65 a die plate provided with a facet and with a casting groove bounding said facet, said die plate being further provided with an air hole extending through a part of said plate to a point flush with the surface with 70 said facet, and further provided with an air duct merging into said air hole and extending partially across said facet, for the purpose of enabling air to escape from said casting groove into said air hole, in the 75 form of a capillary film.

2. A die plate provided with a casting groove and with a portion bounded by said casting groove and formed into a facet, said portion having an air hole and being provided with an air duct interrupting said facet and merging into said air hole, in order to facilitate the escape of air, traveling in the form of a capillary film from said casting groove into said air duct.

NORMAN D. STURGES.
